Primary Examiner — Michael C Stout*Assistant Examiner* — Eric Eldone Tormanen(74) *Attorney, Agent, or Firm* — Patterson + Sheridan, LLP(57) **CLAIM**

The ornamental design for a surgical console, as shown and described.

DESCRIPTION

FIG. 1 is perspective view of a surgical console showing our new claimed design;

FIG. 2 is a front elevational view thereof;

FIG. 3 is a back elevational view thereof;

FIG. 4 is a right-side elevational view thereof;

FIG. 5 is a left-side elevational view thereof;

FIG. 6 is a top plan view thereof; and,

FIG. 7 is a bottom plan view thereof.

The broken lines in the figures show portions of the surgical console that form no part of the claimed design.
